HOSIERY FORM SUPPORT

William J. De Witt, Auburn, N. Y., assignor to
 Shoe Form Co., Inc., Auburn, N. Y., a corpora-
 tion of New York

Application April 8, 1938, Serial No. 200,849

1 Claim. (Cl. 223—120)

This invention relates to an improvement in hosiery form supports, and more particularly to an improvement in a base for supporting a hosiery form, being a further development of the invention disclosed in my copending application Serial No. 166,973, filed October 2, 1937.

The primary object of this invention is to provide a hollow base for a hosiery form, the base being of transparent material and adapted to contain liquid or other material which serves not only to weight the base and thereby steady the hosiery form, but also to provide with the hosiery on the form a blending or contrasting color effect.

15 A further object of this invention is to provide such a base which comprises a hollow transparent standard which is substantially pyramidal and has at the top an opening through which the interior may be filled and a cup-shaped member attached to the side of the standard and adapted to receive and hold the toe of a hosiery form.

20 These and other objects appear from a consideration of the following description and the disclosure in the accompanying drawing which 25 forms a part thereof, and in which:

Fig. 1 is a view in side elevation of a hosiery form base embodying this invention;

Fig. 2 is a cross-sectional view of such base;

30 Fig. 3 is a cross-sectional view, taken along the line 3—3 in Fig. 1; and

Fig. 4 is a plan view of such base.

The base 10 comprises a standard 11 and a cup-like member 12 mounted thereon. As indicated by a dotted line, the member 12 is adapted to receive and hold the toe of a hosiery form of the type shown in my Patent No. 2,003,707, dated June 4, 1935.

40 The standard 11 is hollow and has substantially the form of a truncated pyramid, having a plurality of plane panels 15. The open bottom of the standard is normally sealed by a lid 16. At the top of the standard is formed an aperture 17 through which the interior of the standard may be filled with liquid or fluid material by which 45 the base is weighted. A panel at one side of the standard is defined at sides and bottom by a bead 18.

50 The member 12 is similar in contour to a toe portion of the well known type of shoe form and includes a flange 20 which rests upon and is secured to the bead 18. The member 12 and the panel defined by the bead 18 thus cooperate to form the pocket 21 in which the toe of a hosiery form is inserted, as shown in Fig. 1.

One feature of this invention is that the material forming the standard 11 and member 12 is transparent. The contents of the standard 11 are therefore visible as is the toe of the hosiery on the hosiery form. Pleasing effects can thereby be attained by filling the standard with substance which has a color that will blend with or contrast with the color of such hosiery.

5 The standard may, as set forth above, be filled with liquid or fluid material introduced through the aperture 17. This will presumably be done by the dealer or exhibitor and be changed whenever desired. Another advantage is that the shipping weight of the base is reduced, since it is not necessary that the standard be weighted 15 until the base has arrived at the place where the hosiery is to be displayed.

If desired, however, the lid 16 may be removed and the interior of the standard be provided with any suitable material which will fill all or a part 20 of the standard. For example, there may be placed within the standard a small image or similar object which may carry suitable advertising matter.

Similarly the member 12 does not, because of 25 its transparency, adversely affect the appearance of the hosiery.

While one embodiment of this invention has been shown and described, it will be understood that I am not limited thereto and that other embodiments may be made without departing from the spirit and scope of the invention as set forth in the following claim.

I claim:

A support for a hosiery form comprising in 35 combination a hollow base of transparent material having substantially the form of a truncated pyramid with panels in the sides thereof, and provided at the top with an aperture through which material may be introduced to weight the 40 base, and a cup-like member of transparent material fixed to the sides of the base and forming with one of the panels a pocket having an opening at its top above the panels to receive the toe of the hosiery form so as to support the same in 45 an upright position, the panels to the rear and sides of the pocket being shaped so that all parts of the hosiery on the form are clearly visible except the double thickness of the hosiery at the bottom of the toe, the transparency of the base 50 and the pocket blending or contrasting with the hosiery on the form to produce an attractive color effect.

WILLIAM J. DE WITT.
